CLAIM

The ornamental design for a medical instrument, as shown and described.

DESCRIPTION

1. Medical instrument

3. Medical instrument

FIG. 1.1 is a perspective view of a medical instrument;

FIG. 1.2 is an enlarged view thereof;

FIG. 1.3 is a perspective view thereof;

FIG. 1.4 is an enlarged view thereof;

FIG. 1.5 is a top view thereof;

FIG. 1.6 is an enlarged view thereof;

FIG. 1.7 is a bottom view thereof;

FIG. 1.8 is an enlarged view thereof;

FIG. 1.9 is a front view thereof;

FIG. 1.10 is a back view thereof;

FIG. 1.11 is a left view thereof; and

FIG. 1.12 is a right view thereof.

FIG. 3.1 is a perspective view of a medical instrument;

FIG. 3.2 is an enlarged view thereof;

FIG. 3.3 is a perspective view thereof;

FIG. 3.4 is an enlarged view thereof;

FIG. 3.5 is a top view thereof;

FIG. 3.6 is an enlarged view thereof;

FIG. 3.7 is a bottom view thereof;

FIG. 3.8 is an enlarged view thereof;

FIG. 3.9 is a front view thereof;

FIG. 3.10 is a back view thereof;

FIG. 3.11 is a left view thereof; and

FIG. 3.12 is a right view thereof.

Reproductions 1.1-1.12 and 3.1-3.12 show medical instruments for percutaneous release procedures in the treatment of the carpal tunnel and trigger finger syndromes, respec-
